BASEBALL GAME

Edwin L. Slater, Sioux City, Iowa

Application June 15, 1939, Serial No. 279,335

2 Claims. (Cl. 273—89)

My invention relates to a board game for simulating a baseball game.

An object of my invention is to provide a baseball game which can be played by two players, one in the position of a pitcher and the other in the position of a batter.

A further object of my invention is to provide an auxiliary rotating device which imparts a spinning action to the ball or marble with which the game is played and which adds certain features to the game to provide a closer actual simulation to the actual ball game.

A further object of my invention is to provide openings for receiving the driven marble or ball and which opening indicates certain playing conditions.

A further object of my invention is to provide the above mentioned objects in a simple construction.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Figure 1 is a plan view of the game showing the entire arrangement,

Figure 2 is an enlarged sectional detail view taken substantially along the lines 2—2 of Figure 1,

Figure 3 is a plan detail of the rotating device, and

Figure 4 is a side elevation of the rotating device.

I have used the character 10 to designate generally the base of a board or the field which includes several openings 11 which are formed in the bottom 10 leaving a slight thickness as a base. The receiving openings 11 are spaced approximately as shown and positioned about the same are a series of vertical pins 12 which are adapted to stop the motion of the ball or marble so that the same in many cases will fall into the openings 11.

Extending about the perimeter of the bottom 10 are the side walls 13 and the walls 14. Spaced from the left hand side wall 13 is a vertical barrier 15 which leaves a space at 16. Attached at 17 to one of the end walls 14 is the spring member 18 which is bent inwardly to the striking portion 19 and is then bent backwardly and thence into the grasping portion 20. Attached at the other end of the board and along the same side wall 13 is the covering member 21 which extends into

the curved portion 22 which curved portion extends vertically down to the base 10 of the board. (See Figure 2.)

The space between the member 21 and the base 10 is indicated by the character 23 which is hollow for the reception of the marbles and the small wooden cylinders which represent the players, one of such players being indicated by the character 24 in Figure 1 and which is simply a circular block of a fairly substantial height. Attached at 25 within the opening 23 is a further spring member 26 which is bent into the striking portion 27 which is bent backwardly and then into the grasping portion 28. Pivotally attached to the base 10 is the rotating member 29 which member rotates upon the screw 30 which screw is recessed within the base as at 31. A small washer 32 spaces the base 33 of the member 29 apart from the base 10 and a nut 34 is attached above the base allowing a fairly loose engagement therewith so that the device 29 can rotate freely.

The member 29 includes a series of upwardly projecting fins 35 which extend approximately radially to the center with the exception, however, that the members 35 do not pass directly through the center of the device. The fins 35 are of a substantial width and are bent upwardly from the horizontal portions 36. A further single fin 37 is bent upwardly from the portion 36 which fin, however, is substantially less than half the width of the fins 35 and which fin 37 is positioned at a greater distance from the screw 30 leaving a wider space at 38 therebetween.

A series of slots such as 39, 40, 41 and 42 which receive the markers 43 are arranged to show strikes, balls, outs and scores as shown which markers 43 can be moved along the slots to indicate the respective conditions in the game. Side lines such as indicated by the characters 44 and 45 indicate the foul lines which are marked upon the base 10 and a further substantially square mark 46 represents the usual diamond with the character 47 representing the various bases.

The game is played in the following manner: A marble 48 is placed within the space 16 and next to the portion 19 of the spring 18. One of the players draws the spring 18 rearwardly by grasping the portion 20 and then releases the same. The striking action of the portion 19 against the marble 48 will impel the marble rapidly along the passage 16 where it will strike against one of the fins 35 or the fin 37 of the member 29. This will cause the member 29 to rotate rapidly

in the direction of the arrow 49 which imparts a certain amount of spin to the marble, which then passes along the curved portion 22. The other player who is positioned at the other end of the board at this moment draws back the spring 26 by grasping the portion 28 and releases the same and tries to strike the marble with the portion 27.

After striking, the marble will be hit to any one of the pockets 11 or will land upon the field in some position either inside of the foul lines or outside of the same and if the marble falls into one of the pockets, the playing situation as called for in the pocket is observed. If the player at the spring 26 does not strike the ball, this is termed a "strike." In case the ball jams within the member 29 or shoots off to one side of the board, this is called a "ball."

It will be observed that the smaller fin 37 by leaving a larger space at 38 in some cases will permit the marble 48 to pass therethrough in the direction of the arrow 50. This allows the ball to be carried outside and away from the striking portion 27 and is therefore called a "ball." This provides an interesting element in the game since in some cases the spinner will be in a position to allow the ball to pass through or the rotation of the member 29 may carry the fin to this position and thereby provides a deviation from the fin structure of uniform width. It will be observed, however, that the fins 35 are wide enough to prevent the ball from passing between the fins 35 and the stud 30. This is to provide a positive spinning action regardless of position of the spinner with the exception, however, of that case when the smaller fin 37 is substantially at right angles to the path of the marble.

Certain rules can be observed such as if a man 24 is on a base and is struck by the marble, it can be called a double play. Any rules can be employed as desired, such as for instance, when the ball lands on board without falling in a pocket, it will naturally be a "single" allowing the player to advance, and other modifications can be employed as desired.

It should be noted principally, however, that the provision of the two spring actions provides a means for forming a game device allowing opposing teams with an interesting feature of actual conditions as a thrown ball being employed, also the spinner or rotating member 29 provides further important features in that it produces spin to allow the ball to follow the curved contour more closely and also provides interesting de-

viations such as the striking portion 27 to allow the ball to shoot off to one side. Other advantages are readily apparent.

It will now be seen that I have provided a baseball game which can be played by two players simulating a pitcher and a batter, which includes auxiliary means to impart a spinning action to the ball as well as other desirable features, which includes means attendant therewith to duplicate actual playing conditions and which can be manufactured at a simple cost.

Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

1. A board baseball game comprising a playing field having a plurality of pockets for indicating certain baseball conditions, means positioned on said field to propel a marble within said pockets including a spring member for impelling said marble, a further spring member positioned opposite to said spring member to simulate the approximate position of a batter for striking a marble impelled by said spring member, a curved member positioned adjacent to said further spring member for causing passage of a marble thereagainst, a rotating member pivotally attached to the board adapted to impart spin to the marble, said rotating member including a plurality of vertical fins against which said marble strikes, an upwardly projecting stud attached to said base upon which said rotating member is pivoted, a part of said fins extending toward said stud to prevent a marble passing therebetween and one of said fins being of restricted width to allow passage of a marble between said fin and said stud.

2. A board baseball game comprising a playing field, means for impelling a marble along one side of said field, a rotating member pivotally attached in the path of said marble, said rotating member including a plurality of vertical fins against which said marble strikes, an upwardly projecting stud attached to said field upon which said rotating member is pivoted, a part of said fins extending toward said stud to prevent a marble passing therebetween, and one of said fins being of restricted width to allow passage of a marble between said fin and said stud.

EDWIN L. SLATER.
